HAND BELT SANDING PLANE

Albert F. Hill, Big Spring, Tex.

Application May 24, 1938, Serial No. 209,764

2 Claims. (Cl. 51—187)

This invention relates to a hand sanding plane, and it consists in the constructions, arrangements and combinations herein described and claimed.

It is an object of the invention to provide a plane body which is longitudinally contractible and extensible for the purpose of removing and securing a sanding belt.

It is also an object of the invention to provide a quickly detachable hand grip for the plane, facilitating removal, adjustment or replacement of the sanding belt.

It is a still further object of the invention to provide a sanding plane of simple, durable construction which may be manufactured at a low cost.

Additional objects, advantages and features of invention will be apparent from the following description considered in conjunction with the accompanying drawing, wherein

Figure 1 is a side elevation of the sanding plane.

Figure 2 is a top plan view thereof.

Figure 3 is a cross section on the line 3—3 of Figure 2.

Figure 4 is a fragmentary sectional view illustrating the guide means between the two sections of the plane.

There is illustrated a main body 10 of any suitable material, substantially rectangular in shape, the outer end 11 of which is slightly rounded, the inner end 12 being cut flush at right angles. The face of the end 12 has a pair of spaced bores 13 slidably receiving dowel pins 14 of an adjacent end section 15. The face of the section carrying the dowel pins is complementary to the adjacent face of the body 10 and will abut thereagainst, at times. The outer end 16 of the section 15 is also rounded. The main body 10 and the section 15 is faced with a felt or rubber pad 17 which preferably extends upwardly around the ends 11 and 16, as clearly shown in Figure 1.

The main body 10 and the section 15 are extensibly interconnected for the purpose of securing a sanding belt 18, as will appear as the description proceeds.

A toggle link 19 is pivotally connected, as at 20, to opposite sides of the main body 10, the other end of the links being pivoted to companion links 21, as at 22, each of which is pivotally connected to the end section 15 by means of pivots 23. Suitable detent means 24 are formed in the links 19-21 to retain the links in extended positions in the present instance, a ball and socket construction being shown. It should be understood that in the extended position of the links 19 and 21,

the sections 10 and 15 will be moved to their outermost positions and retained in such relation by engagement of the balls and sockets of respective links.

From the description thus far, it will be apparent that by breaking the links 19 and 21 in a direction as indicated by dotted lines, the section 15 will be drawn inwardly into abutting engagement with the section 10, and in this position the endless sanding belt 18 may be readily installed over the ends 11 and 16 of the felt or pad 17, and by extending the links to their full line positions, the end 15 will be moved longitudinally outward, tensioning the sanding belt 18 into proper extended position for sanding operations.

In order to manipulate the sanding plane, I provide a handle 25, which is of a length so as to lie within the opposite ends of the pad 17 and includes a forward knob 26 and a rear knob 27. These knobs function as means for gripping and manipulating the sanding device in the manner of a woodworking plane. The handle 25 includes spring clips 28 at the ends of a width to straddle the sections 10 and 15, each clip comprising resilient arms 29 adapted to grip opposite sides of the sections 10 and 15. Thus, since the arms 29 are resilient, they may be quickly detached from the sections 10-15 permitting adjustment or replacement of the belt 18.

While I have shown and described a preferred construction, this is by way of illustration only, and I consider as my own all such modifications in structure as fairly fall within the scope of the appended claims.

I claim:

1. A sanding plane comprising a pair of spaced aligned sections adapted to receive a sanding belt therearound, one of said sections having dowel pins complementary to bores of the other section, link members pivotally connected upon opposite sides of one section, similar links connected to opposite sides of the other section, the links upon respective sides being pivotally connected, the links being arranged in partial overlapped relation, one of the links having a ball member adjacent its end, the other link having a socket complementary to the ball when in one position of movement of the links, a resilient pad on the face of each section for support of one reach of the sanding belt, a detachable handle for the plane, said handle consisting of a body member, fore-and-aft knob members on the body member, and spring clip arm members on the body member adapted to embrace the sides of respective sections.

2. A sanding plane comprising a pair of spaced aligned sections adapted to receive a sanding belt therearound, one of said sections having dowel pins complementary to bore of the other section, link members pivotally connected upon opposite side of one section, similar links connected to opposite sides of the other section, the links upon respective sides being pivotally connected, the

links being arranged in partial overlapped relation, one of the links having a ball member adjacent the end, the other link having a socket complementary to the wall when in one position of movement of the links, and a resilient pad on the face of each section for support of one reach of the sanding belt. 5
